UNITED STATES PATENT OFFICE.

FREDERICK NELSON PITTS, OF THOROLD, CANADA.

CARDING-MACHINE.

SPECIFICATION forming part of Letters Patent No. 788,555, dated May 2, 1905.

Application filed July 7, 1902. Renewed March 28, 1905. Serial No. 252,530.

To all whom it may concern:

Be it known that I, FREDERICK NELSON PITTS, manufacturer, of the township of Thorold, in the county of Welland, in the Province of Ontario, Canada, have invented certain new and useful Improvements in Carding-Machines, of which the following is the specification.

My invention relates to improvements in carding-machines; and the object of the invention is to devise a simple, cheap, and efficient automatic means whereby the wool or other stock or material from the primary carding-machine, no matter whether of low or high grade, may be doubled or mixed and conveyed directly, if preferable, to the finishing-machine, and thereby effect a saving in material or stock and a saving of time and produce a yarn of better quality than has been produced in machines of this class as at present constructed.

A subsidiary object is to keep the fiber straight as it passes from one machine into the other, so that the fibers are fed endwise and not broken or disturbed and the bat is fed in doubled or crimped form.

The invention consists, essentially, of a doubling or mixing roller connected to the discharge end of the primary machine, such roller being arranged to come in contact with the doffer-roller, a vibrating comb suitably driven and designed to coact with the mixing-roller, a conveyer having one end near the doffer and mixing roller and having its opposite end extending into proximity with the feed-roller of the finishing-machine, a compressor-bar suitably operated in proximity with the feed-roller of the feeding-machine, a licker-in roller located substantially above the uppermost feed-roller and coacting therewith, and a lumper-roller located substantially above the licker-in roller, the parts being arranged and constructed as hereinafter more particularly explained.

Figure 1 is a perspective view showing a portion of the discharge end of the primary machine and the feed end of the finishing-machine, exhibiting therebetween the parts involved in my invention. Fig. 2 is a similar view from the opposite side of the ma-

chine. Fig. 3 is a longitudinal section. Fig. 4 is a perspective detail of the evener-arm. Fig. 5 is a perspective detail of the worm-gear, whereby the mixing-roller is given an oscillating movement.

In the drawings like letters of reference indicate corresponding parts in each figure.

A is the doffer-roller of the primary machine, the shaft of which is supported in suitable bearings B on the main frame.

C is the gear-wheel, secured on the end of the shaft of the doffer.

D is the mixing-roller, which is provided with a suitable spindle d, which is journaled in suitable bearings on the frame of the machine.

d' is a gear-wheel secured on the end of the shaft d of the mixing-roller.

d² is an intermediate idler connecting the gear-wheels C and d'.

E is an endless conveyer made, preferably, of slats e, connected to endless leather belts e', which are carried at one end by the roller F, having a spindle supported in suitable journals on the main frame of the primary machine, and on spindles G, supported in suitable journals on the main frame of the finishing-machine at the other end.

H is a cross-shaft suitably journaled on suitable bearings H' on the frame of the machine.

h is a stripping-comb secured thereon designed to operate and to be vibrated in front of the mixing-roller.

I do not describe the mechanism whereby the comb is vibrated, as it is of ordinary construction.

I' are the feed-rollers of the finishing-machine, journaled in suitable bearings i on the main frame of the finishing-machine.

J is the licker-in roller, supported on suitable bearings J'.

J² is the lumper-roller, and J³ is the wiper-roller designed to operate against the lumper-roller.

j' is a gear-wheel secured on the spindle j of the lower feed-roller.

j¹⁰ is a gear secured to the end of the wiper-roller. This gear meshes with the gear j', so that when the wiper-roller is driven the

100

lower feed-roller will be driven also by the gears j^1 and j^{10} .

j^2 is a pinion on the opposite end of the spindle of the lower feed-roller.

5 j^3 is a pinion on the end of the conveyer-roller, and j^4 is an intermediate idler-pinion connecting the pinions j^2 and j^3 .

j^5 is a pinion on the end of the upper feed-roller designed to mesh with the pinion on 10 the lower feed-roller.

The wiper and lumper rollers are provided with pulleys j^6 j^7 , driven by belts j^8 j^9 from the main drive of the machine.

15 K is a cross rocking shaft supported on suitable arms on the frame of the finishing-machine and designed to rock loosely thereon.

K^2 is an arm secured to one end of the cross-shaft K.

20 L is a bar slidably held in the guide-brackets l l' , secured to the frames of the primary and finishing machines, respectively. k is a slot formed in the arm K^2 , through which passes a bolt k' , provided with a nut k^2 , securing the arm to the bar L.

25 K^5 is a crank-arm secured on the shaft K^{6x} , suitably journaled on the frame of the machine.

30 K^7 is a link connecting the bar L with the crank-arm K^5 . The crank-arm K^5 is driven by means of the pulleys K^6 K^7 , secured on the shaft K^{6x} , and spindle of the doffer-roller, respectively, carrying the connecting driving-belt K^8 .

35 M is a pressure-bar connected by the arms m to the shaft K.

N N are evener-arms which abut the edges of the bat as it passes from the mixing-roller. The evener-arms N are formed in two portions n n' , provided, respectively, with the 40 vertical and longitudinal slots n^2 n^3 . The portion n is secured by a bolt n^4 , passing through vertical slot into the bearing of the mixing-roller. The portion n' is secured to the portion n by a bolt n^5 , passing through 45 the longitudinal slot n^3 into the portion n .

45 m' represents evener-arms secured in front of the feed-rollers to the main frame in a similar manner as the eveners N N.

50 D' is a saddle-piece straddling the bearing of the shaft d and having collars D^2 , which encircle the shaft.

D^4 is a worm-gear secured to the shaft d .

55 d^4 is a saddle-piece designed to straddle the worm-gear D^4 in a similar manner to the saddle-piece D' . The pieces D' and d^4 are provided with extension-arms d^5 d^6 .

D^5 is a worm-wheel loosely secured upon the bolt d^7 , and d^6 is a cam forming part of the wheel D^5 .

60 D^7 is an extension-piece secured at right angles to the extension-arm d^5 and provided with a slotted portion d^8 , in which the cam d^6 is designed to operate.

As the worm-gear revolves it rotates the 65 worm-wheel, and the cam carried thereby re-

volves in the slot, and thereby carries the spindle longitudinally in its bearings, imparting a reciprocating movement thereto.

Having described the principal parts involved in my invention, I will briefly describe 70 the operation of the same.

The wool passes beneath the doffer-roller in the form of a fleece and is caught by the mixing-roller, which oscillates, as hereinafter described, thereby evenly spreading the wool 75

against the evener-arm, so as to make the bat of uniform width. The wool then falls onto the conveyer in the form of a carded fleece.

The conveyer is driven at a very low rate of speed, preferably in proportion of one inch of 80 travel to one hundred inches of travel of the mixing-roller. By this means the fleece is

gathered or crimped together in the form of a continuous bat, as shown in Fig. 3, with its fibers perfectly mixed. The beater-rod M 85

insures the bat being even in width before it passes between the feed-rollers by forcing it outwardly against the eveners. If there are any lumps or inequality of thickness in the

bat, they are removed by the lumper-roller, 90 which picks up the lump and carries it back to the wiper-roller. The adjacent peripheries of the lumper and licker-in rollers

rotate in the same direction, and the adjacent peripheries of the lumper and wiper rollers 95

rotate in the opposite direction, while the adjacent peripheries of the wiper and licker-in rollers rotate in the same direction. Thus

the lump is picked from the fleece by the lumper-roller, which carries it around to the 100 wiper-roller, which tears the lump therefrom,

so as to pull the lump apart, and then the wiper-roller carries it back into the fleece at the periphery of the licker-in roller, thus insuring the bat passing in a perfectly even 105

state into roving. It will be seen from this description that the wool is fed forward automatically from the primary carding-machine into the finishing - machine, with its fibers always moving in the same longitudinal 110

direction in relation to each other, so that the fibers are kept in a longitudinal form parallel to each other, are crimped together as it passes over the apron by reason of the difference in the rate of movement of the apron or 115

conveyer and the mixing - roller, thereby thoroughly mixing the fibers longitudinally, and thus the wool is carried forwardly in an unbroken continuous bat into the finishing-machine.

120 By my method very short fibers may be used and fed directly in parallel relation and evenly to the finishing-machine, thereby producing a much stronger roving in a minimum space of time out of an inferior quality of 125

fleece.

What I claim as my invention is—

1. In a carding-machine the combination with the primary machine and its doffer-roller, mixing-roller and comb, of a conveyer 130

rotating at a lower rate of speed than the doffer-roller and means for driving the conveyer as and for the purpose specified.

2. In a carding-machine, the combination with the primary machine having the doffer-roller, mixing-roller and comb, and the feed-rollers of the finishing-machine, of a conveyer located intermediately, and means for driving the same at a lower rate of speed than the doffer-roller, as and for the purpose specified.

3. In a carding-machine, the combination of the primary machine having the doffer-roller, the feed-rollers of the finishing-machine, a conveyer located intermediately, means for driving the same at a lower rate of speed than the doffer-roller, a mixing-roller and a vibrating comb located in front of the doffer-roller, as and for the purpose specified.

4. In a machine of the class described, the combination of the doffer-roller, of the primary machine, the feed-rollers of the finishing-machine, a conveyer located between the doffer and the feed rollers, means to rotate the same at a lower rate of speed than the doffer, a mixing-roller located in front of the doffer-roller, as and for the purpose specified.

5. In a machine of the class described, the combination of the primary machine having the doffer-roller, the feed-rollers of the finishing-machine, a conveyer located between the doffer and the feed rollers, means to drive the same at a lower rate of speed than the doffer, a mixing-roller located in front of the doffer-roller and a vibrating comb located immediately in front of and coacting with the mixing-roller, as and for the purpose specified.

6. In a machine of the class described, the combination of the primary machine having the doffer-roller, the feed-rollers of the finishing-machine, an endless conveyer located between the doffer and the feed rollers, means for driving the same at a lower rate of speed than the doffer-roller, a mixing-roller located immediately in front of the doffer-roller and rotating at a higher rate of speed than the conveyer, evener-arms located at each side of the conveyer in front of the mixing-roller, means for imparting a reciprocating movement to the mixing-roller and a vibrating comb operating in conjunction with the mixing-roller, as and for the purpose specified.

7. In a machine of the class described, the combination with doffer-roller, feed-rollers, endless conveyer located between the doffer-roller and feed-rollers, and a vibrating comb arranged adjacent to one end of the conveyer, of a mixing-roller located between the doffer-roller and the comb, a bracket secured to the spindle of the mixing-roller, a cam-wheel rotatably held thereon, means for driving the cam, a slotted bracket secured to the main frame of the machine in which said cam operates and evener-arms located at each side of the said conveyer in front of the mixing-roller as and for the purpose specified.

8. In a machine of the class described, the combination with the doffer-roller, feed-rollers, endless conveyer located between the doffer-roller and feed-rollers, and a vibrating comb arranged adjacent to one end of the conveyer, of a mixing-roller located between the doffer-roller and comb and provided with a worm-thread on the spindle thereof, a bracket encircling said shaft on each side of the said worm and a worm-wheel rotatably held on said bracket and meshing with the worm-thread on the spindle, a cam-wheel secured to or forming part of said worm-wheel, a slotted bracket secured to the frame of the machine in which the said cam is designed to operate and evener-arms located on each side of the said conveyer in front of the mixing-roller as and for the purpose specified.

9. In a machine of the class described, the combination with the reciprocating mixing-roller, the comb and endless conveyer, of evener-arms located at each side of the conveyer, and secured to the main frame and abutting the edges of the bat as it passes from the mixing-roller as and for the purpose specified.

10. In a machine of the class described, the combination with the feed-rollers of the finishing-machine and the endless conveyer, of evener-arms located at each side of the conveyer in proximity to the feed-rollers to abut the edges of the bat and means for spreading the bat against the evener-arms, as and for the purpose specified.

11. In a machine of the class described, the combination with the feed-rollers of the finishing-machine and the endless conveyer, of evener-arms located at each side of the conveyer in proximity to the feed-rollers and abutting the edges of the bat, a rocking bar located above the conveyer between the evener-arms, a beater-bar connected to the cross-bar and means for imparting a rocking motion to said shaft as and for purpose specified.

12. In a machine of the class described, the combination with the feed-rollers of the finishing-machine and the endless conveyer, of evener-arms located at each side of the conveyer in proximity to the feed-rollers and abutting the edges of the bat, a rocking cross-bar located above the conveyer between the evener-arms, a beater-bar connected to the cross-bar, an arm secured to the end of the said cross-bar, a horizontal slidable bar secured in suitable guideways to the frame of the machine, a suitably-driven shaft supported on suitable bearings on the frame of the machine, a crank-arm secured thereto connected to the slidable bar as and for the purpose specified.

13. In a carding-machine, the combination with the primary machine having the doffer-roller, a conveyer, a mixing-roller and

comb coating with the doffer-roller, said parts delivering the wool in the form of a crimped or doubled bat as and for the purpose specified.

5 14. In a carding-machine, the combination with the primary machine having the doffer-roller, a conveyer, a mixing-roller and a

cam coating with the mixing-roller, said parts delivering the wool in the form of a crimped or doubled bat as and for the purpose specified.

FREDERICK NELSON PITTS.
